UNITED STATES PATENT OFFICE.

JOHN J. OLHASSO, HENRY F. GOSS, AND JOSEPH H. POS, OF PORTLAND, OREGON,
ASSIGNORS TO INTERNATIONAL BOLTING TOOL CORPORATION, A CORPORA-
TION OF OREGON.

BOLTING MACHINE.

Application filed January 18, 1921. Serial No. 438,092.

To all whom it may concern:

Be it known that we, JOHN J. OLHASSO and HENRY F. Goss, both citizens of the United States, and JOSEPH H. Pos, a subject of the Dominion of Canada, and all three residents of Portland, in the county of Multnomah and State of Oregon, have invented a new and useful Bolting Machine, of which the following is a specification.

10 Our invention relates to improvements in bolting machines, in which bolts, nuts, lag screws and such like machine elements are tightened by means of a socket wrench driven by a small motor and interposed 15 planetary gears.

Preliminary to the riveting of steel ship hulls, boilers, tanks, bridges, buildings, and similar structures, the members comprising said structures must be bolted together with 20 a large number of bolts. So far the only practical method known has been to tighten these bolts by hand with a wrench or spanner.

The purposes of our invention are to produce a tool which is comparatively simple 25 to construct; which can be handled by one man; which is adapted to be used with any standard make of electric, hydraulic or air motor; and which does the work more 30 speedily, economically and efficiently than any other device known at present.

Measured in ratio of performance, our 35 tool produces a more satisfactory result at less than one-tenth of the cost of the old method.

We attain these objects with the mechanism illustrated in the accompanying drawings, in which—

Fig. I is a plan view of the entire apparatus with part of the handle broken away.

Fig. II is a side view of Fig. I.

Fig. III is a section through Fig. I along the line A—A.

Fig. IV is a plan view with the cover removed, as indicated by the line B—B in Fig. II.

Fig. V shows the spindle detached.

Figs. VI and VII illustrate alternate arrangements of the planetary pinions.

50 Similar numerals refer to similar parts throughout the several views.

In the cylindrical housing 1, having a projecting hub 2 is revolubly mounted a working head 3. Pressed into the flange 4

of the working head are the pivots 5, and 55 mounted for free rotation on the pivots are the planetary pinions 6. These pinions mesh with an internal gear 7, the latter being firmly secured against rotation in the wall of the housing 1 by one or more set 60 screws 8. With this arrangement it will be obvious that a revolution of the pinions in the direction of the arrows 9 in Fig. IV will propel the pinions themselves bodily in the direction of the arrows 10, and thus 65 cause the working head to revolve at a slow speed dependent upon the ratio between the teeth on the pinions and the teeth on the internal gear.

Rotation of the planetary pinions is effected by a central gear 11 forming a part 70 of the spindle 12. At one side of the central gear the spindle rests in a socket 13 in the working head; at the other side the cover 14 furnishes the support. The shank 75 of the spindle is slightly tapered and flattened at the free end to form a firm connection with the axis of a suitable motor 15 (Fig. II). A collar 16 on the spindle between gear and cover reduces wear at this 80 place to a minimum.

The cover is secured to the housing by means of the cap screws 17, a sufficiency of metal 18 being allowed in the wall of the housing where the screw holes enter.

A handle 19 inserted in a socket 20 in the cover gives the operator greater leverage to prevent the housing from turning. The cap screw 21 holds the handle in place.

To enable the use of various sized motors, 90 the outer wall of the socket 20 is properly fashioned to furnish a guideway on which the slotted leg 22 of an angle may be slidably supported. The cap screw 21 holds this leg in proper adjustment. The other 95 leg 23 with its thumb screws 24, engages a slotted extension leg 25, and in the hole 26, at the end of the extension leg, the motor is held.

Only one planetary pinion is actually 100 needed to cause a rotation of the working head, but two pinions disposed opposite each other are preferred to equalize the thrust and to reduce the unit stresses in the teeth. Where a further reduction of unit stresses 105 is desired, three gears, as shown in Fig. VII, or four gears as shown in Fig. VI, may be employed to good advantage.

The socket wrench 27 has a square shank which enters a square hole 28 in the working head, said wrench can therefore be easily replaced by a larger or smaller one. 5 A grease cup 29 in the cover furnishes the lubricant for the moving parts in the interior of the housing.

The numerals 30, 31 and 32 represent bearing bushings in the hub 2, the working 10 head 3, and the cover 14, respectively. If worn out, these bushings can be withdrawn and exchanged for new ones.

The reinforcing ribs 33 impart strength at the junction of the hub and cylinder.

15 Having thus described our invention, it will be seen that our objects have been accomplished, and, though we have shown the preferred form of construction, we reserve to ourselves the right to make minor changes

providing we do not violate the spirit and 20 principle of our invention.

We claim:

In a bolting machine, the combination of a cylindrical housing having an internal gear, a cover at one end of the housing, a 25 hub at the other end of the housing, a working head having a flange rotatably mounted in the housing, a geared spindle entering the housing through the cover and mounted in a bearing in the working head, planetary 30 pinions pivotally mounted on the flange of the working head, the teeth of said planetary pinions meshing with the internal gear and with the geared spindle.
